UNITED STATES PATENT OFFICE.

WILLIAM H. GEORGE, OF FAIRFIELD, IOWA, ASSIGNOR TO THE DEXTER COMPANY,
OF FAIRFIELD, IOWA, A CORPORATION OF IOWA.

OPERATING MECHANISM FOR WASHING-MACHINES.

1,154,005.

Specification of Letters Patent. Patented Sept. 21, 1915.

Application filed April 16, 1914. Serial No. 832,162.

To all whom it may concern:

Be it known that I, WILLIAM H. GEORGE, a citizen of the United States, and a resident of Fairfield, in the county of Jefferson and State of Iowa, have invented certain new and useful Improvements in Operating Mechanism for Washing-Machines; and I do hereby declare that the following is a full, clear, and exact description thereof, reference being had to the accompanying drawings, and to the letters of reference marked thereon, which form a part of this specification.

This invention relates to an improvement in operating mechanism for washing machines and consists of the matters hereafter described and more particularly pointed out in the appended claim.

The invention is here shown as applied to the operation of a washing machine of the familiar dolly type, consisting of a tub having a hinged top in which is supported a shaft which depends into the tub and which is provided at its lower end with a dolly or dasher adapted for rotary, alternating movement. The operating mechanism is of the lever actuated, high-speed-gear type and includes a prime moving lever fulcrumed to the side of the tub and a fly wheel, together with a mechanism on the one hand for imparting rotary, alternating movement to the dolly shaft and mechanism on the other hand for imparting a continuous rotary movement to the fly wheel.

In the drawings: Figure 1 is a view in side elevation of a washing machine provided with my improved operating mechanism. Fig. 2 is a view in front elevation thereof. Fig. 3 is a detail plan sectional view, said section being indicated by the line 3-3 of Fig. 1.

Referring now to that embodiment of my invention illustrated in the accompanying drawings, 5 indicates the tub, 5^a, a lid hinged to the top thereof, and 6, the usual upright supporting legs therefor, said tub in this case providing the support for the operating mechanism.

8 indicates the dolly or beater which is non-rotatively connected to a dolly shaft 9 that is rotatively suspended from the top of the hinged lid 5^a of the tub. Said shaft 9 has bearing in a sleeve 10 which projects through a suitable aperture formed in said lid and said sleeve is made integral with a

plate 10^a fixed to the upper surface of the lid. 11 indicates a gear fixed to the upper end of the said shaft 9, and 12 indicates a gear case for protecting said gear, said gear case being fixed to the plate 10^a.

Alternating, rotary movement is imparted to the gear 11 by means of a longitudinally reciprocating bar 13 provided near one end and on one lateral edge with a rack 13^a which engages the gear 11. The rack 13^a is held in engagement with the gear 11 by means of an angle plate 14 attached to the top surface of the lid 5^a, and having bearing engagement with the outer lateral edge of the bar 13. The bar 13 is pivotally connected to the upper end of a lever 15 which is fulcrumed intermediate its ends to a bracket arm 16 attached to the side of the tub body near its bottom.

17 indicates a prime mover in the form of a hand lever which is fulcrumed intermediate its ends and nearer its lower end to a bracket arm 18 secured to the side of the tub body.

The levers 15 and 17 are arranged so as to swing in parallel vertical planes and the bracket arms 16 and 18 are made integral with a base plate 19 which is attached to the tub body near its bottom edge, in any suitable manner.

Fixed to the bottom of the tub body 5 and near the center thereof, is a depending bracket member 20. Said bracket member is provided with horizontally extending, laterally spaced studs 21, 22.

23 indicates a vertically arranged fly wheel rotatively mounted on the stud 22. Said fly 23 is provided with a toothed hub 24 and the teeth of said hub are engaged by a vertically arranged large gear wheel 25 which is rotatively mounted on the stud 21. The gear wheel 25 is provided with a crank pin 26 which is operatively connected by a pitman rod 27 to the bottom end of the lever 15.

28 indicates a link which is pivotally connected at one end to the bottom end of the prime moving lever 17 and at the other end to the pitman rod 27 at a point intermediate the ends of said pitman rod and preferably nearer to the end of the same that is connected to the crank pin 26.

It is apparent that the oscillation of the prime moving lever 17 will, through the link 28, the pitman rod 27, the lever 15 and the

rack bar 13, impart a rotary, alternating movement to the dolly shaft 19 and at the same time, said lever will through the link 28, the pitman 27, the gear wheel 25 and the 5 toothed hub 24, impart a continuous rotary motion to the fly wheel 23.

When it is desired to swing the hinged lid 5^a to an open position, the rack bar 13 is 10 swung vertically upward about its pivotal connection with the lever 15 out of the way, thus permitting said lid to be opened.

It will be noted that by the gearing described, an increased leverage is provided for operating the mechanism which actuates 15 the dolly shaft. In addition, this increased leverage is provided in such a manner in the preferred form of the construction shown in the drawings that the two levers, namely, the prime moving lever 17 and the lever 15, 20 move toward and away from the tub body at the same time, so that there is no danger of the lever 15 striking the operator should he inadvertently move his body forward with the lever 17 in operating the machine.

25 While in describing my invention, I have referred to certain details of mechanical construction and arrangement, it is to be understood that the invention is not to be limited thereto except as may be pointed out 30 in the appended claim.

I claim as my invention:

An operating mechanism for washing machines and the like, comprising in combina-

tion with a support having an operating shaft rotatively carried thereby, a prime 35 moving lever fulcrumed to the side of said support, a second lever fulcrumed to said support adapted to oscillate in a plane parallel to the plane of oscillation of said prime 40 moving lever, a device intermediate said second lever and said operating shaft for imparting a rotary, alternating movement to said shaft, a fly wheel having a toothed hub 45 rotatively carried by said support, a gear also carried by said support and adapted to mesh with the toothed hub of said fly wheel, means intermediate said gear and said second mentioned lever for transposing the continuous, rotary movement of said gear into an oscillatory movement of said lever, said 50 means comprising a crank pin on said gear, a pitman rod pivotally connected at one end to said crank pin and having its opposite end pivotally connected to said second mentioned lever and a link pivotally connected at one 55 end to said pitman rod at a point intermediate the ends thereof and at its opposite end to said prime moving lever.

In testimony, that I claim the foregoing as my invention I affix my signature in the 60 presence of two witnesses, this 10th day of April A. D. 1914.

WILLIAM H. GEORGE.
